COMBINED DESK, LOCKER AND BUNK BED UNIT

Kenneth F. Villanova, Providence, R.I., assignor of a
fractional part interest to David R. Villanova, Chepa-
chet, R.I.

Filed Dec. 4, 1972, Ser. No. 311,744

Term of patent 14 years

Int. Cl. D6—05

U.S. Cl. D6—80

FIG. 1

FIG. 2

FIG. 3

FIG. 4

FIG. 5

FIG. 6

FIG. 7

FIG. 1 is a perspective view of a combined desk, locker and bunk bed unit showing my new design;

FIG. 2 is a front elevational view thereof;

FIG. 3 is a rear elevational view thereof;

FIG. 4 is a left side elevational view;

FIG. 5 is a right side elevational view;

FIG. 6 is a top plan view thereof; and

FIG. 7 is a bottom plan view thereof.

I claim:

The ornamental design for a combined desk, locker and bunk bed unit, substantially as shown.
